UNITED STATES PATENT OFFICE.

JOHN PAXTON PETTY, OF READING, ENGLAND.

TEMPORARY BINDER OR LOOSE-SHEET OR THE LIKE HOLDER.

1,148,618.

Specification of Letters Patent. Patented Aug. 3, 1915.

Application filed December 8, 1913. Serial No. 805,361.

To all whom it may concern:

Be it known that I, JOHN PAXTON PETTY, a subject of His Majesty the King of England, residing at Reading, Berkshire, England, have invented certain new and useful 5 Improvements in Temporary Binders or Loose-Sheet or the like Holders, of which the following is a specification.

This invention is for improvements in 10 temporary binders for loose leaves and the like, wherein a pair of clamping bars are associated with means for effecting the clamping of the sheets thereby and with means functioning solely as sheet registering members.

By and in accordance with the present invention a binder of the kind referred to is produced in which the act of disconnecting the clamping bars frees (a) the binder constituents for removal "en bloc" from the binder 20 with the short engaging and registering means remaining threaded therethrough or (b) the sheet engaging and registering means for removal from the binder for replacement by a fresh means or for enabling the binder to be adapted for use with a typewriter or billing machine. The facility for replacing the sheet engaging and registering means by fresh means enables means of 25 longer length to be employed as the binder increases in thickness and thereby the usefulness of the binder is materially promoted.

To the foregoing ends a temporary binder according to the present invention comprises 30 in combination a pair of clamping bars, hinged covers associated therewith, means detachably connecting the clamping bars and operable to draw the clamping bars toward each other and a member longitudinally flexible and transversely relatively 35 rigid in one direction endwise loosely combined with both said clamping bars and said covers to function solely as a sheet engaging and registering member. The term 40 "endwise loosely combined" is to be defined as meaning that the sheet engaging and registering member is free from any endwise fastening to the adjacent surface or parts of the binder against which such member 45 lies, which would require to be loosened to release said member. Thus, in designing the binder, provision may be made for producing such a frictional resistance to endwise displacement of said member that during 50 the ordinary use of the binder endwise creeping of the member is precluded or

minimized to a negligible degree without defeating the object of the invention. Preferably a plurality of such members are employed, and, conveniently the sheet registering members are in the form of leather thongs having an inserted flexible steel strip, but such members may be of any suitable material which form strips which are longitudinally flexible and transversely relatively rigid in one direction; these thongs or strips being adapted to be threaded through eyes in the clamping bars and to have their surplus portions for any given separation of the clamping bars received 60 loosely in the binder covers which are formed hollow for this purpose.

The invention may be conveniently and advantageously carried into practice as shown in the accompanying drawings in 75 which:—

Figure 1 is an inside view of a binder in the opened position, the cover plate on the inner side of each back being removed. Fig. 2 is a section on line $\alpha\alpha$ of the binder 80 shown by Fig. 1. Fig. 3 is a section corresponding to Fig. 2 but showing the binder clamping loose sheets therein, and Fig. 4 is a view of the rear portion of a sheet to be secured within the binder. Fig. 5 is an 85 enlarged sectional detail view.

The drawings show a binder which comprises clamping bars 1, and 2, which are hinged, respectively, to the backs or covers 3, 4. These clamping bars are adapted to 90 be drawn together to clamp the loose sheets therebetween, as by means of the longitudinally flexible members 5, engaging with toothed wheels 17 (Fig. 5) rotatably mounted on a rotatable longitudinal rod 18 in the 95 clamping bar 2, the ends of such members 5 being detachably engaged with the clamping bar 1 by the headed link 6 engaging within correspondingly shaped slots in the clamping bar 1. The members 5 attached 100 to the clamping bar 1 pass through openings 13 in the clamping bar 2, and thence enter the hollow cover 4 where they are preferably connected to light springs 14 which pass around guide wheels 15 and are 105 attached to a fixed point 16 of the cover 4. In this way possibility of the members 5 sagging or jamming, especially between the bar 2 and the cover 4, is avoided. The leather thongs 8, which function solely as 110 sheet registering members, are loosely engaged with the clamping bars 1 and 2 by

being merely slid through the eyes 9, and the free end of such thongs 8 pass loosely into the covers 3 and 4 by way of the openings 10, whereby the sheet registering means 5 are detachably engaged with the binder with such registering members being free from any endwise fastening to the parts of the binder against which they lie. For the purpose of affording such a frictional 10 resistance to endwise displacement or creeping of the thongs 8 that during the ordinary use of the binder, the thongs will substantially keep their proper positions in the binder, the thongs 8, as depicted in the case 15 of the outer pair, may be adapted to co-act with converging edges 12 of the covers so that the thongs are somewhat transversely flexed. Such an arrangement in no wise defeats the object of the invention and secures the said desirable control of the endwise loosely combined thongs in a very simple, inexpensive, and effective manner. The sheet registering means 8, thus combined with the binder, may be very readily removed, as when the clamping bars 1, 2, have been allowed to be moved apart by operating the member 5 and the headed links disconnected from the bar 1 in known manner, the thongs are free to be slid away 20 from the binder, such thongs being of such a longitudinal flexibility as to readily admit of such a sliding disconnection. By thus being able to move the thongs the sheets contained in the binder are readily adapted 25 to be typewritten thereon by the class of typewriter for use in operating upon flat sheets. For this purpose holes are formed in the clamping bars in known manner, so that the binder may be passed over posts 30 secured to a table of the said typewriting machine, perforations being also formed in the loose leaves to admit of this. When the binder has been placed over the posts the top cover may be removed and the thongs 35 also removed, whereby in known manner the sheets may be slid up the posts and turned over onto posts, which with the aforesaid posts form the limbs of an inverted U-shaped member, so that any desired 40 sheet may be placed into position for being operated on by the typewriter.

Further advantage in the present construction is present in that all the sheets contained in the binder may be removed 45 "en bloc" with the sheet registering means remaining threaded therethrough which therefore permits such removed sheets and thongs to be placed in another binder without disturbing the sheets.

60 The depicted construction herein described is one that I have found to work well. But it is to be understood that the invention is susceptible to many structural variations without going beyond the scope 65 thereof.

Having thus described my invention what I claim and desire to secure by Letters Patent is:—

1. A temporary binder comprising in combination a pair of clamping bars, hinged 70 covers associated therewith, means detachably connecting the clamping bars and operable to draw the clamping bars toward each other, and a member longitudinally flexible and transversely relatively rigid in 75 one direction endwise loosely combined with both said clamping bars and said covers for bridging the space between the clamping bars to function solely as a sheet engaging and registering member, whereby the act of 80 disconnecting the clamping bars frees (a) the binder contents for removal "en bloc" from the binder with the sheet engaging and registering member remaining threaded therethrough or (b) the sheet engaging and 85 registering member for removal from the binder for replacement by a fresh member, or for enabling the binder to be adapted for use with a typewriting or billing machine, substantially as described. 90

2. A temporary binder comprising in combination a pair of clamping bars, hinged covers associated therewith, means detachably connecting the clamping bars and operable to draw the clamping bars toward 95 each other and a plurality of members longitudinally flexible and transversely relatively rigid in one direction endwise loosely combined with both said clamping bars and said covers for bridging the space between the clamping bars to function solely as sheet 100 engaging and registering members, whereby the act of disconnecting the clamping bars frees (a) the binder contents for removal "en bloc" from the binder with the sheet 105 engaging and registering members remaining threaded therethrough or (b) the sheet engaging and registering members for removal from the binder for replacement by fresh members, or for enabling the 110 binder to be adapted for use with a typewriting or billing machine, substantially as described.

3. A temporary binder comprising in combination a pair of clamping bars, hinged 115 covers associated therewith, means detachably connecting the clamping bars and operable to draw the clamping bars toward each other, and a member longitudinally flexible and transversely relatively rigid 120 in one direction combined so as to be free from any endwise fastening which would require to be loosened to release the member, with both said clamping bars and said covers for bridging the space between the clamping bars to function solely as a sheet 125 engaging and registering member, whereby the act of disconnecting the clamping bars frees (a) the binder contents for removal "en bloc" from the binder with the sheet en- 130

gaging and registering member remaining threaded therethrough or (b) the sheet engaging and registering member for removal from the binder for replacement by a fresh member, or for enabling the binder to be adapted for use with a typewriting or billing machine, substantially as described.

4. A temporary binder comprising in combination a pair of clamping bars, hinged covers associated therewith, means detachably connecting the clamping bars and operable to draw the clamping bars toward each other, and a plurality of members longitudinally flexible and transversely relatively rigid in one direction combined, so as to be free from any endwise fastening which would require to be loosened to release the members, with both said clamping bars and said covers for bridging the space between the clamping bars to function solely as sheet engaging and registering members, whereby the act of disconnecting the clamping bars frees (a) the binder contents for removal "en bloc" from the binder with the sheet engaging and registering members remaining threaded therethrough or (b) the sheet engaging and registering members for removal from the binder for replacement by fresh members, or for enabling the binder to be adapted for use with a typewriting or billing machine, substantially as described.

5. A temporary binder comprising in combination a pair of clamping bars, hinged covers associated therewith, means detachably connecting the clamping bars and operable to draw the clamping bars toward each other, and a member longitudinally flexible and transversely relatively rigid in one direction endwise loosely combined, subject to creeping preventing provision by flexure thereof, with both said clamping bars and said covers for bridging the space between the clamping bars to function solely

40 ject to creeping preventing provision by flexure thereof, with both said clamping bars and said covers for bridging the space between the clamping bars to function solely

as a sheet engaging and registering member whereby the act of disconnecting the clamping bars frees (a) the binder contents for removal "en bloc" from the binder with the sheet engaging and registering member remaining threaded therethrough or (b) the sheet engaging and registering member for removal from the binder for replacement by a fresh member or for enabling the binder to be adapted for use with a typewriting or billing machine substantially as described.

6. A temporary binder comprising in combination a pair of clamping bars, hinged covers associated therewith, means detachably connecting the clamping bars and operable to draw the clamping bars toward each other, and a plurality of members longitudinally flexible and transversely relatively rigid in one direction endwise loosely combined, subject to creeping preventing provision by flexure thereof, with both said clamping bars and said covers for bridging the space between the clamping bars to function solely as sheet engaging and registering members, whereby the act of disconnecting the clamping bars frees (a) the binder contents for removal "en bloc" from the binder with the sheet engaging and registering members remaining threaded therethrough or (b) the sheet engaging and registering members for removal from the binder for replacement by a fresh member, or for enabling the binder to be adapted for use with a typewriting or billing machine, substantially as described.

In testimony whereof I affix my signature 80 in presence of two witnesses.

JOHN PAXTON PETTY.
